UNITED STATES PATENT OFFICE.

SAMUEL S. STOLP, OF MANSFIELD, OHIO, ASSIGNOR TO THE OHIO BRASS COMPANY, OF MANSFIELD, OHIO, A CORPORATION OF NEW JERSEY.

ELECTRICALLY-OPERATED TRACK SWITCH.

Application filed December 19, 1923. Serial No. 681,591.

To all whom it may concern:

Be it known that I, SAMUEL S. STOLP, a citizen of the United States of America, residing at Mansfield, in the county of Rich-
land and State of Ohio, have invented cer-
tain new and useful Improvements in an
Electrically-Operated Track Switch, of
which the following is a specification.

My invention relates to electrically and
automatically operated track switches.

One of the objects of my invention is to produce a system by which the track switch is electrically controlled by the operator on a moving car as he approaches the switch by application of the well known principle of "power on" and "power off" the motors.

Another object of my invention is to produce a system in which there is independent means for controlling the circuits leading to the track switch for directional operation of the switch.

Another object of my invention is to provide a system which will prevent the burning out of the track switch operating mechanism if the car remains too long in cooperative relation with the system.

My invention resides in the new and novel combination, construction and relation of the various electrically operated switches, circuits and other parts hereinafter more fully described and disclosed in the drawings.

In the drawings accompanying my specifi-
cation:

Fig. 1 is a schematic view showing the various circuits usually found in electrically operated cars and taken into account in the design and operation of my invention.

Fig. 2 is a schematic drawing showing the various parts under normal conditions.

Fig. 3 is a schematic drawing of my invention showing the relation of the various parts at the instant the moving car comes into cooperative relation with my system with "power off" the motors.

Fig. 4 is a schematic drawing showing the relation of the various parts after the car has been in cooperative relation with the system for a predetermined time after engag-
ing the same with "power off" the motors but while cooperation still exists.

Fig. 5 is a schematic drawing of my invention showing the relation of the various parts at the instant the car engages the sys-

tem in cooperative relation and while it re-
 mains in cooperative relation with "power
on" the motors.

Referring to Fig. 1 I have shown the various car circuits which I give consider-
ation to which comprise the heating system
H, the light system L and the compressor
circuit F, all receiving current from the
trolley wire or conductor through the cur-
rent collector W which is mounted on the
car by means of the pole T and which ap-
paratus also have a ground connection G.
These circuits operating these apparatus and
current flowing therein I term the auxiliary
car circuits and auxiliary current respec-
tively. The cars are also equipped with
motors M for moving the cars and a con-
troller C operated by the car operator and
for controlling the current to the motors M.
The auxiliary circuits are not under the con-
trol of the controller and this fact I must
take into account in designing the system.
When the controller is thrown to "power
off" position no current will flow through
the motors M, but when it is thrown to the
"power on" position a current of consider-
able magnitude will flow through the motors
and thence to ground G.

Referring to Fig. 2 I employ a contact
pan P to be engaged by the collector W and
which is positioned adjacent the trolley con-
ductor 1. The pan P comprises two parallel
contact members 2 and 3 normally insulated
from each other, but one having an elec-
trical connection with the trolley conductor
through the medium of the coil winding 4
on the switch A and the conductors 5 and
6 connecting the coil 4 to the trolley con-
ductor and contact member 2. The member
3 is in electrical connection with the con-
ductor 1 only when the collector W engages the
pan P. The members 2 and 3 and the con-
ductor 1 are so related that while the col-
lector engages the pan it will be out of engage-
ment with the conductor 1. When the col-
lector W is in contact with the pan the
members 2 and 3 are electrically connected
and if the car operator has his controller
positioned for "power on" the motors, it
will be evident that a heavy current will flow
from the trolley wire through the coil 4 and
its connections, through the member 2 and
thence to ground through the motor M. If,
however, the controller is set at the "power

off" position no current will flow through the motors M, but the auxiliary current will flow through the apparatus H, L and F. As this current may amount to considerable and 5 in some instances approach close to the motor current, I must design the coil 4 so that it will not pick up its armature 7, on account of the auxiliary current flowing therethrough, but will pick up the arm 7 10 on account of the motor current when it flows through the coil 4.

I also employ a track switch S provided with a switch tongue 8 and two solenoids 9 and 10, each having one terminal connected 15 to the ground through the common conductor 11. The switch is also provided with a reciprocating plunger 12 connected to the tongue 8 by the connecting link 13. When the solenoid 9 is energized the plunger 12 20 will be drawn inwardly and move the switch tongue to the "straight ahead" position. This solenoid is operated whenever the collector engages the pan with "power off". When the solenoid 10 is energized the 25 plunger will be drawn outwardly and the switch tongue moved to the "curve" position and this operation takes place whenever the collector engages the pan with "power on".

I also employ a switch B provided with 30 an operating coil 14 having one terminal connected to the switch arm 7 by the conductor 15 and the other terminal connected to the contact member 3 by the conductor 16. Whenever the collector engages the pan with 35 "power off" the coil 14 will be energized and its armature 17 will be raised. This operation is due to the circuit leading from the trolley pan 3 through the conductor 16, coil 14, conductor 15, conductor 18 which 40 connects the arm 7 with the remaining terminal of the solenoid 10, conductor 11 to ground G. The coil 14, however, is not energized if the collector engages the pan with "power on" as later explained.

I also employ an electrically operated 45 switch C provided with two coils 19 and 20 and its switch arm 21 which is normally held closed due to the normal energizing of the coil 20. The switch arm 21 is connected 50 to the trolley conductor 1 by the conductor 22. One terminal of the coil 20 is connected to the conductor 22 or the arm 21 by means of the conductor 23 and the conductor 24 connects the other terminal of the coil to 55 the conductor 25 which connects the arm 17 with the remaining terminal of the solenoid 9, therefore, there is at all normal times a 60 circuit to energize the coil 20 from the trolley conductor by way of the solenoid 9 to ground. This will maintain the switch C normally closed.

Each of the switches A, B and C are provided with a fixed core or a movable core of magnetizable material operating the respective switch arms, all as well known in the

art. Each switch A, B and C is provided with a contact 26, 27 and 28 respectively and all contacts are connected by a common conductor 29. The terminals of the coil 19 are connected to the conductor 23 which is common to both coils 19 and 20 and to the conductor 29 by means of the conductor 30. The coil 19 is normally de-energized for the reason that its one terminal is connected to the conductor 29 which normally has no 75 ground connection.

When the switch B is closed the conductor 29 is connected to ground as evident through the solenoid 9, but even this does not permit current to flow through the coil 19 as then the switch arm 21 acts as a short circuit to the coil 19 and the coil 20 will also be deprived of its operating current for the reason that the conductor 25 will then be in electrical connection with the trolley conductor by a low resistance path, and this will be the equivalent of placing the trolley on both terminals of the coil 20 which is equivalent to a short circuit upon this coil. If the switch B remains 90 closed a sufficient length of time the switch C will open after the magnetization of its core drops off sufficiently. As soon as the switch C opens, if the switch B still remains closed due to the collector engaging the pan P the coils 19 and 20 will have the short circuit removed and current will then flow through each coil and energize the same. However, I connect these coils to operate in 95 differential and, therefore, the energizing of these coils will not permit the arm 20 to close, but will remain open as long as the switch B remains closed, which in turn will remain closed as long as the collector engages the pan and the switch B will close 100 whenever the collector engages the pan with "power off" the motors.

If the collector engages the pan with "power on" the coil 4 will be strongly energized and will close the arm 7 with its contact 26. Current will also tend to flow from the contact 3 through the coil 14 and to ground, but I so proportion the time of closing of the switches A and B so that A 110 will close prior to the switch B. As soon as the switch A closes, it will be evident that we have a similar condition with respect to the coil 14 as the coils 19 and 20 when the switch B closes, that is, when the switch A is closed we virtually place a short circuit around the coil 14 and if this short circuit takes place before the switch B can close then the switch B will be prevented from closing. If, however, the switch B should close prior to the closing of the switch A then the switch B will open after a predetermined time, but this I prevent, as already explained, by causing the switch A to be more sensitive in pick up than the switch B.

The windings of the coils 14, 19 and 20 are of very high resistance so that only a very small current will flow therethrough and the winding 4 is made of very low resistance and large wire in order to properly take care of the current which must flow therethrough and thence through the motors. The switch C does not open when the switch A has been closed by "power on" the motors. As soon as either switch A or B closes current will flow through the solenoid 10 or 9 respectively thereby energizing these coils and moving the switch arm to the "curve" or "straight ahead" position respectively.

It sometimes happens that the car will engage the pan with "power off", but will come to rest with the collector in engagement with the pan and if it were not for the switch C opening the solenoid 9 would be very apt to burn out under a prolonged flow of current, therefore, the switch C is designed with a time release factor permitting the current to flow through the solenoid 9 for a sufficient time to properly saturate the solenoid. If the car operator intends to pass the pan with "power on", it is an exceedingly unusual circumstance for him to come to rest with the collector in engagement with the pan and, therefore, I provide no protection for "power on" operation of the system, that is, the switch C will not open for the reason that there is no short circuit about the coil 20, but the coil 20 will be in series with the coil 9, the two directly across the mains, that is, from trolley to ground and the coil 20 will be energized the same as under normal conditions (Fig. 2) and hence switch C will remain closed when the switch A is closed.

To review the operation of the system, if a car operator desires to move "straight ahead" he will cause the collector W to engage the pan P with "power off" the motors and as soon as the collector engages the pan the parts will assume the position shown in Fig. 3 and for the reasons already explained. If the car comes to rest with the collector in engagement with the pan the switch C will open after a predetermined time and the parts will assume the relation shown in Fig. 4, the switch B remaining closed as long as the collector is in engagement with the pan.

If the car operator desires to take the curve he will move across the pan with "power on" and the parts will then assume the relation shown in Fig. 5 and remain so until the collector has passed off the pan, regardless of the length of time the collector engages the pan with "power on".

There are, of course, many modifications and re-arrangements which may be made of the parts and which will suggest themselves to those skilled in the art and which will

fall within the scope of my invention, therefore, I do not wish to be limited other than by my claims.

I claim:

1. A switch operating system comprising a trolley conductor, a contact pan provided with a pair of contact members to be engaged by a current collector, an electrically operated track switch, a power circuit leading from the conductor and provided with normally open branches to operate the switch to the proper position, an electrically operated switch to close one of the branch circuits when the collector engages the pan with "power on", an electrically operated switch to close the other circuit when the collector engages the pan with "power off", means to prevent the second electrically operated switch closing when the first is closed and means to open the power circuit after the second electrical switch has been closed a predetermined time.

2. A switch operating system comprising a trolley conductor, a contact pan provided with a pair of contact members to be engaged by a current collector, an electrically operated track switch, a power circuit provided with normally open branches to operate the switch to the proper position, an electrically operated switch to close one of the branch circuits when the collector engages the pan with "power on", an electrically operated switch to close the other circuit when the collector engages the pan with "power off", means to prevent the second electrically operated switch closing when the first is closed and means to open the power circuit after the second electrical switch has been closed a predetermined time.

3. A switch operating system comprising a trolley conductor, a contact pan provided with a pair of contact members to be engaged by a current collector, an electrically operated track switch, a power circuit provided with normally open branches to operate the switch to the proper position, an electrically operated switch to close one of the branch circuits when the collector engages the pan with "power on", an electrically operated switch to close the other circuit when the collector engages the pan with "power off", means to prevent the second electrically operated switch closing when the first is closed, means to open the power circuit after the second electrical switch has been closed a predetermined time and means to prevent the opening means closing after having opened and while the second electrical switch is closed and while the collector engages the pan.

4. A switch operating system comprising a trolley conductor, a contact pan provided with a pair of contact members to be engaged by a current collector, an electrically operated track switch, a power circuit pro-

vided with normally open branches to operate the track switch in the desired direction, an electrically operated switch in each of the branch circuits to close the branch circuits one at a time depending whether the collector engages the pan with "power off" or "power on", and a normally closed switch to open the power circuit and provided with means to maintain it open after a predetermined time after the collector engages the pan.

5. A switch operating system comprising a trolley conductor, a contact pan provided with a pair of contact members to be engaged by a current collector, an electrically operated track switch, a power circuit provided with normally open branches to operate the track switch in the desired direction, an electrically operated switch in each of the branch circuits to close the branch circuits one at a time depending whether the collector engages the pan with "power off" or "power on", and a normally closed switch operating to open the power circuit only when the collector engages the pan with "power off".

6. A switch operating system comprising in combination, a trolley conductor, a contact pan provided with a pair of contact members to be engaged by a current collector, an electrically operated track switch, a power circuit provided with normally open branch circuits to operate the track switch in the desired direction, an electrically operated switch in each branch circuit to close the branch circuits one at a time depending whether the collector engages the pan with "power on" or "power off", one of the electrical switches arranged to be short circuited by the closing of the other switch to prevent its closing and electrically operated means to open the power circuit after a predetermined time.

7. A switch operating system comprising in combination, a trolley conductor, a contact pan provided with a pair of contact members to be engaged by a current collector, an electrically operated track switch, a power circuit provided with normally open branch circuits to operate the track switch in the desired direction, an electrically operated switch in each branch circuit to close the branch circuits one at a time depending whether the collector engages the pan with "power on" or "power off", an electrically operated switch to open the power circuit and means operating to open the last said switch after one of the said branch circuit switches has closed.

60 8. An electrically operated track switch comprising in combination, a trolley conductor, means to operate the track switch electrically, a contact pan to be engaged by

a current collector, a circuit provided with branches for operating the track switch 65 operating means, an electrically operated switch controlling each branch circuit separately, each switch provided with a single operating coil connected to the pan and an electrically operated switch to open the said 70 circuit after the collector has engaged the pan for a predetermined time.

9. In a switch operating system the combination of an electrically operated track switch, a contact pan to be engaged by a current 75 collector, a branched circuit conducting current to the track switch to operate the switch in the direction desired, a control switch in each branch operating to control the branch circuits separately and a control 80 switch in the circuit leading to the branch circuits and operating to open said circuit when the system is working "power off" only.

10. In a switch operating system the combination of an electrically operated track switch, a contact pan to be engaged by a current 85 collector, a branched circuit conducting current to the track switch to operate the switch in the direction desired, a control 90 switch in each branch operating to control the branch circuits separately and a control switch in the circuit leading to the branch circuits and means to prevent the closing of the last said control switch when 95 the collector first engages the pan with "power off" and then changes to "power on".

11. In a switch operating system the combination of an electrically operated track switch, a contact pan to be engaged by a current 100 collector, a branched circuit conducting current to the track switch to operate the switch in the direction desired, a control switch in each branch operating to control the branch circuits separately and a control 105 switch in the circuit leading to the branch circuits and means comprising two differentially connected coils to maintain last said switch open while the collector engages the pan with "power off".

12. A track switch operating system comprising in combination, a trolley conductor, means to operate the track switch electrically, a contact pan to be engaged by a current collector, a normally closed switch connected to the conductor, a branched circuit connecting the normally closed switch with the track switch operating means, an electrically operated and normally open switch in each branch and arranged to control each branch circuit separately and means to open the normally closed switch after the collector has engaged the pan for a predetermined time.

In testimony whereof I affix my signature.
SAMUEL S. STOLP.
